COMBINED TOOTHBRUSH AND TUMBLER HOLDER

Jack T. Turner, 808 Cary Campbell Road,
Fort Pierce, Fla.

Filed Nov. 23, 1962, Ser. No. 72,577

Term of patent 14 years

(Cl. D4—3)

FIG. 4.

FIG. 1 is a front perspective view of a combined toothbrush and tumbler holder, showing my new design;

FIG. 2 is a side elevational view thereof;

FIG. 3 is a top plan view thereof; and

FIG. 4 is a modified form of the combined toothbrush and tumbler holder shown in FIGS. 1, 2 and 3.

I claim:

The ornamental design for a combined toothbrush and tumbler holder, as shown and described.
